(**) Term: **14 Years**

(57) **CLAIM**

(21) Appl. No.: **29/173,318**

The ornamental appearance of a plasma arc torch tip with swirl holes, as shown and described.

(22) Filed: **Dec. 26, 2002**

DESCRIPTION

Related U.S. Application Data

(63) Continuation-in-part of application No. 29/166,921, filed on Sep. 4, 2002.
(51) **LOC (7) Cl.** **15-09**
(52) **U.S. Cl.** **D15/144**
(58) **Field of Search** D15/144-144.2;
219/121.44-121.5

FIG. 1 is a perspective view of the plasma arc torch tip with swirl holes from the top;

FIG. 2 is a perspective view thereof from below, wherein the dashed lines indicate changes in surface contour;

FIG. 3 is a perspective view thereof from above and rotated from FIG. 1;

FIG. 4 is a side elevation view thereof;

FIG. 5 is a side elevation view thereof, rotated 90° from FIG. 4;

FIG. 6 is a top plan view thereof, wherein the dashed lines indicate changes in surface contour; and,

FIG. 7 is a bottom plan view thereof.
